[57] CLAIM

The ornamental design for a machine for making mousse for hair treatment and the like, substantially as shown and described.

DESCRIPTION

FIG. 1 is a perspective view of a machine for making mousse for hair treatment and the like, showing my new design.

FIG. 2 is a top plan view;

FIG. 3 is a rear elevational view;

FIG. 4 is a left elevational view;

FIG. 5 is a front elevational view; and

FIG. 6 is a bottom plan view.

Fig. 1.
